(57) **CLAIM**

The ornamental design for a vaporizer device, as shown and described.

DESCRIPTION

FIG. 1 is a front perspective view of the vaporizer device showing a first embodiment;

FIG. 2 is a rear perspective view of the vaporizer device of FIG. 1;

FIG. 3 is a left side elevational view of the vaporizer device of FIG. 1;

FIG. 4 is a right side elevational view of the vaporizer device of FIG. 1;

FIG. 5 is a bottom plan view of the vaporizer device of FIG. 1;

FIG. 6 is a top plan view of the vaporizer device of FIG. 1;

FIG. 7 is a front elevational view of the vaporizer device of FIG. 1;

FIG. 8 is a rear elevational view of the vaporizer device of FIG. 1;

FIG. 9 is a front perspective view of the vaporizer device showing a second embodiment; and,

FIG. 10 is a front elevation view of the vaporizer device of FIG. 9, the rear perspective view, the left side elevation view, the right side elevation view, the bottom plan view, the top plan view, and the rear elevation view being the same as in the embodiment of FIG. 1 and therefore not illustrated in the drawing disclosure for a second time.

The broken lines immediately adjacent shaded surfaces represent the bounds of the claimed design and form no part of the claimed design; all other broken lines in the drawings depict portions of the vaporizer device that form no part of the claimed design.
